UNITED STATES PATENT OFFICE.

ARNOLD PFAU, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

HYDROELECTRIC INSTALLATION.

Application filed September 6, 1921, Serial No. 498,720, and in Switzerland September 8, 1920.

This invention relates in general to power installations, and it has particular relation to hydro-electric power installations where the hydraulic machine is operative under or against a widely varying head.

Turbines of hydraulic power plants which are subject to a highly variable head such, for instance, as the high and low tide of the ocean, suffer a considerable loss in the power developed. This is particularly the case with very low heads where even a slight change in the head amounts to quite a considerable portion of the full normal head. For instance, if the normal net head is 4.5 meters, the highest head 6 meters, and the lowest head two meters, the total average amounts to 4 meters or 88.8% of the normal head.

It is well known that the number of revolutions or speed of a turbine varies with the square root of the net head. For instance, if the revolutions are 100 per minute on the 16 meters head, it is 100 divided by $\sqrt{2}$, or about 71 revolutions under 8 meters, and it is 100 divided by $\sqrt{4}$, or 50 revolutions, that is, half of the former amount when the head has dropped to $\frac{1}{4}$ of the maximum head.

If a turbine is directly connected to an alternating current generator, it should always operate at the same number of revolutions, otherwise the number of periods or frequency of the current would change, and this would render parallel operation with other generators impossible. Therefore, if a turbine were normally designed for 100 revolutions under 16 meters net head, it would have to develop under 4 meters head, not 50 revolutions, but twice as much, that is, 100 revolutions, in order to produce current of the proper number of periods or frequency. A turbine operating at a speed which is 100 per cent higher than normal, however, shows such unfavorable hydraulic efficiencies that it becomes uncommercial to still use a turbine for such operating conditions.

The speed of the generator could be maintained normal by using in steps belt drives

or similar devices with proper transmission ratios. This arrangement, however, is impossible where large units are used and particularly when the turbine and generator are directly coupled, which is the most favorable mechanical solution.

The power developed by the turbine is even more sensitively affected by a change in the net head: first, on account of the head itself, second, on account of the discharge capacity. It is well known that

$$Q_1:Q_2 = \sqrt{H_1}:\sqrt{H_2}, \text{ where}$$

Q_1 =quantity of water under the head H_1 .

Q_2 =quantity of water under the head H_2 .

And

$$HP_1:HP_2 = H_1:\sqrt{H_1}:H_2:\sqrt{H_2}, \text{ where}$$

HP_1 =power at head H_1 .

HP_2 =power at head H_2 .

80

65

70

The capacity or power of the turbine, however, is also subjected to a variation in the efficiency of the turbine, and this deviates more from the best value as the number of revolutions or speed is greater or less than the normal speed.

Therefore, if the power or capacity, for instance, under 16 meters net head, is 4000 H. P., then it is, according to the above formulæ, only 500 H. P. under 4 meters, and this does not as yet consider the loss of power due to reduced efficiency. Now, if the turbine must maintain its 100 revolutions, it would have to run twice as fast as is necessary in order to maintain its normal efficiency. Therefore, the efficiency will drop to such extent that nothing will be left of the 500 H. P. In other words, the turbine will produce no power and, therefore, represents a dead capital investment.

For medium or high variable heads or, in general, for conditions which permit of the use of horizontal shaft units, the problem of the economical utilization of head can be solved by arranging the hydraulic parts in two separate hydraulic elements, one located on each side of the generator. The Francis turbine which applicant has disclosed in United States Patent No. 1,023,585, dated

90

85

95

April 16, 1912, and which is a double overhung Francis turbine, can be employed in such a manner that one side utilizes the high head and the opposite side utilizes the low head. In this case, the absolute number of revolutions of the two turbine sides are naturally the same, whereas the individual capacities of the turbines are selected in accordance with the corresponding heads and quantities of water required to suit the capacity of the generator.

Horizontal shaft units can not well be employed for widely variable low heads for several reasons; therefore, in such cases the arrangement of two turbines can not be practically employed, particularly in cases where direct coupling to the generator is required.

The constructions for which patent is herewith applied, includes such as provides a suitable solution of the problem, inasmuch as there are employed, not two different turbines, but rather two different generators. This may be seen from the accompanying drawings, especially Figure 1, the drawings disclosing an embodiment of my invention, various novel features of which will be apparent from the drawings and the description herein considered in connection therewith and will be more particularly pointed out in the claims.

In the accompanying drawings:

Fig. 1 is a partly sectional elevation of a hydroelectric installation embodying features of this invention.

Figs. 2 and 3 are schematic showings of a speed-controlling governor and its method of operation.

In accordance with the disclosure of the drawings, the turbine A is directly coupled with the electric generator unit B, made up of the generator elements B_a and B_b , and the exciter C. All rotating parts of this unit are carried on the thrust bearing D. The turbine may be automatically controlled by a governor acting on the regulating shaft E.

The generator B consists of a rotor fixed on the main shaft and having two sets of poles B_1 and B_2 so arranged that the set B_1 produces the required number of periods or frequency p at a speed n and a number of poles x , and the other set B_2 produces the same number of periods p at a speed n' and x' poles. Similarly, two separate stator elements S_1 and S_2 are provided, corresponding to the two sets of poles B_1 and B_2 , respectively, the field element B_1 and the stator S_1 constituting the generator B_a and the field element B_2 and its stator S_2 constituting the generator B_b . The exciter C is so dimensioned that it furnishes current for either one of the two alternator sets.

Let us now assume that the turbine is to utilize any head between the limits H and H_1 . Assuming now that this head is divided

in two heads, h and h' , in such a way that h varies between the limits H , a maximum, and H_m , a minimum, and h' varies between the limits H_m , a maximum, and H' , a minimum. For each of these two heads, h and h' , the most favorable speed n and n' of the turbine is so selected that the desired uniform frequency p is obtained with the corresponding even number of poles. For instance, if the best speed of the turbine for head h be 150 and for head h' be 120, then pole set B_1 has 40 poles and the other pole set B_2 has 50 poles, if current of a frequency of 50 cycles per second is required.

Under the low head h' , the turbine naturally develops less power at full gate than it does under the high head h , therefore, generator B_b can be designed for a correspondingly smaller capacity in order to operate at best efficiency.

The speed of the whole unit A—B—C—D can be held within desirable limits by an automatic governor of known construction. If the governor is driven mechanically, that is, if it is driven from the main shaft directly, then two transmissions must be provided, corresponding to the two different speeds n and n' of the turbine, for instance, two belts with corresponding pulleys and couplings.

Another method for controlling the two speeds n and n' can be seen from Figures 2 and 3 and can be accomplished in the manner described hereinbelow.

Figure 2 shows schematically a servo-motor M of well known construction, such as is used for controlling the guide-vane openings of turbines. The regulating valve V receives fluid pressure, as indicated at K, and admits same, according to the position of the regulating valve piston V_1 , either to a passage K_1 communicating with the front side of the regulating piston M_1 of the servo-motor M , or to a passage K_2 communicating with the rear side of the regulating piston M_1 . The motion of the regulating piston M_1 is transmitted to a relay R. A speed governor P receives its revolutions through a drive T from the turbine shaft and transmits the motion of the shifting collar or stud of the governor to the floating lever V—P—R. As soon as the regulating valve piston V_1 is raised out of its mid position, fluid pressure K reaches the front side K_1 of the regulating piston M_1 , moving the latter until the regulating valve piston V_1 is brought back to its former mid position. This is attained by the relay R and the floating lever R—P—V in such a way that the forward motion of the regulating piston M_1 produces an upward motion of the end R of the floating lever, causing the regulating valve piston V_1 to be lowered after it had first been raised by the speed governor.

The corresponding strokes of the collar of

the speed governor P produce strokes f' and f on the relay in the following proportion:

$$5 \quad s' = f' \cdot (P-V) = s = f \cdot (P-V), \quad (R-V)$$

where f and f' are strokes of the relay R corresponding to strokes s and s' , respectively, of the collar of the speed governor P, and $(P-V)$ is the length of that portion of the floating lever between the speed governor P and the regulating valve V, and $(R-V)$ is the total length of the floating lever between the relay R and the regulating valve V.

15 To each position of the collar there corresponds a certain number of revolutions or speed of the speed governor, if the design of the latter is static. If we assume that the revolutions or speed corresponding to the highest position of the speed governor is n_t , as shown in the diagram of Figure 3, that of the mid position n_m , and that of the lowest position n_o , then the value

$$25 \quad (1) \quad \frac{n_t - n_o}{n_m} = d_o$$

is conventionally termed the total degree of speed variation of the speed governor; and the values

$$30 \quad (2) \quad \frac{n_2' - n_1'}{n'} = d'$$

and

$$35 \quad (3) \quad \frac{n_2 - n_1}{n} = d$$

where d' is the degree of speed variation between speeds n_2' and n_1' , or corresponding positions of the governor collar, and d is the degree of variation between speeds n_2 and n_1 , or corresponding positions of the governor collar. These values d' and d then indicate the corresponding degrees of speed variation of the part strokes of the collar of the speed governor, or of corresponding relay strokes f' and f . With reference to the function of the servo-motor M, f' and f are generally termed "active strokes" of the speed governor, that is, the strokes necessary for producing the total stroke of the regulating piston V.

By shifting the hand wheel R_2 along the relay rod R_1 in upward or downward direction, these active relay strokes f' and f can be distributed at will over the whole stroke F, Figure 3. From this it follows that the speeds n' and n , or the mid positions of the corresponding active strokes of the speed governor, as indicated in Figure 3, are such that these corresponding mid positions are located within the total stroke of the speed governor produced by the speeds n_t and n_o , and this consequently controls the corresponding speeds of the turbine.

If the total stroke of the collar of the speed governor is selected large, as also the corresponding difference in the speeds n_t and n_o , that is, the corresponding degree of variation of the speed governor is

$$70 \quad (1) \quad d_o = \frac{n_t - n_o}{n_m}$$

then it is possible to control by the same governor for the speeds n and n' of the turbine A (Figure 1) pertaining to the two generator units B_a and B_b . According to the selected position of the hand wheel R_2 (Figure 2), we can, therefore, regulate around the mid position of the relay.

For example: Assume that $d_o = 40\%$, $d' = d = 6\%$, $n = 150$, and $n' = 120$: then $n_m = 135$ and from formula (3), we obtain $n_2' = 154.5$, and $n_1' = 145.5$ from formula (2), we obtain $n_2 = 123.6$, and $n_1 = 116.4$ from formula (1), we obtain $n_t = 162$, and $n_o = 108$. The spaces 1, 2, 3 and 4, indicated in Figure 3, therefore, correspond to differences in numbers of revolutions of 7.5, 10.5, 11.4, and 8.4, respectively, and therefore still permit a substantial variation of both regions of speed n and n' in upward and downward direction.

With this arrangement, therefore, we can obtain the result that both operating speeds n and n' can be controlled with the same drive of speed governor and with the same speed governor. To insure this result, means are provided for adjusting the position of the end R of the lever V-P-R on the relay rod R_1 , a hand wheel R_2 being the specific means shown for securing the desired result.

The springs of the governor are of such strength as to produce the desired governing effect through a wide active range, to thereby obtain a regulating effect that produces a plurality of constant speeds of the turbine, these speeds corresponding to different settings of the hand wheel R_2 on the rod R_1 . This desired regulation is such that the full stroke of the regulating or compensating mechanism, such as the valve V_1 of the servo-motor, corresponding to the full stroke f , f' in either direction from such normal speeds, corresponds to only partial stroke of the governor fly ball device, the effect being such as to produce constant speed independently of a variation in the load of the turbine between substantially no load and the desired limit of overload; and further, this desired regulation to produce constant speed at variable load is obtainable for any one of widely variant operating speeds, such as might correspond to operation of the turbine under conditions of variable head.

While the hydro-electric unit described above finds great utility when connected

with a consumption or distribution circuit whose frequency is definitely established by means other than said unit, nevertheless, it finds considerable utility when it is the only power unit connected to or establishing the frequency of the distribution circuit, for through the means described for maintaining a plurality of definite operating speeds for the generating element, the unit is readily operative to furnish a supply of electrical power to such distribution circuit at the desired definite operating frequency.

It may also be remarked that a combination B_a-B_b-C can be so arranged that A 15 serves as a pump instead of a turbine in which case B_a and B_b serve as two corresponding motors instead of generators in such a way that the fact that the electrical part B_a-B_b has two different operating 20 speeds permits operation of the pump to produce two different lifts.

It may furthermore be remarked that the 25 turbine A and the generator elements B_a-B_b of such a unit could be so built that A acts as a turbine, first rotating in a given direction and delivering electrical energy with one of the two generators B_a or B_b transforming such energy, under the speed n or n' , respectively into electric energy of 30 the constant number of periods of frequency p , or that the turbine A rotates in a direction opposite to the former and operates as a pump absorbing energy which is furnished by the motors B_a-B_b , formerly operating as 35 generators, the energy supplied to the motors being at the common frequency but the motors operating at the different speeds n and n' respectively.

It should be understood that the invention 40 is not limited to the exact details and construction shown and described, for obvious modifications will occur to one skilled in the art.

It is claimed and desired to secure by 45 Letters Patent:

1. A hydro-electric unit for operation under conditions of widely varying head, comprising a hydraulic machine operative at two different normal speeds dependent upon 50 the variable net head, and an electrical element comprising two alternating current dynamo-electric machines operatively connectible to said hydraulic machine to provide for transfer of energy in either direction between either of said dynamo-electric machines and said hydraulic machine, said dynamo-electric machines being operable to 55 produce electrical energy of the same frequency when each is driven by said hydraulic machine operating at a different one of said two normal operating speeds.

2. A hydro-electric unit for operation under conditions of widely varying head, comprising a hydraulic turbine operative at two

different normal speeds dependent upon the 65 variable net head, and an electrical generator element comprising two alternating current generators operatively connectible to said hydraulic turbine to be driven thereby, said generators being operable to produce 70 electrical energy of the same frequency when each is driven by said turbine operating at a different one of said two normal operating speeds.

3. A hydro-electric unit for operation under conditions of widely varying head, comprising a hydraulic machine operative as a pump of the rotary impeller type at two different normal speeds dependent upon the 75 variable net head, and an electrical element 80 comprising two machines operable as alternating current motors each of said motors having a synchronous operating speed different from that of the other and operatively connectible to said hydraulic machines 85 to drive the latter as a pump at one of said two normal speeds.

4. A hydro-electric unit for operation under conditions of widely varying head, comprising a hydraulic machine operative either 90 as a turbine or a pump of the rotary impeller type at two different normal operating speeds dependent upon the variable net head, and an electrical element comprising two alternating current dynamo-electric machines each operative either as a generator or a motor and operatively connectible to said hydraulic machine to provide for transfer of energy in either direction between said hydraulic machine and either of said 95 dynamo-electric machines, said dynamo-electric machines being operable as generators to produce electrical energy of the same frequency only when each is driven by said hydraulic machine at a different one of said 100 two normal operating speeds.

5. A hydro-electric unit for operation under conditions of widely varying head, comprising a hydraulic turbine operative at two different normal speeds dependent upon the 110 variable net head, an electrical element comprising two alternating current generators operatively connectible to said hydraulic turbine to be driven thereby, said electrical element being operable to produce electrical 115 energy of the same frequency when driven by said turbine operating at different ones of said two normal operating speeds, and a speed-controlling governor for said turbine having a wide degree of speed variations, 120 said governor being provided with shiftable collar having a large collar stroke and having associated therewith a compensating servo-motor, the active stroke of said speed governor required for the control of said 125 compensating servo-motor being only a fraction of the total collar stroke, whereby two active collar strokes may be utilized di-

- rectly for controlling the two normal operating speeds of said generators, namely, the upper part of the collar stroke for the region of the higher speed corresponding to 5 operation of the turbine under the higher head, and the lower part of the total collar stroke for the region of the lower speed corresponding to operation of the turbine under the lower head.
10. 6. A hydro-electric installation for operation under conditions of widely varying head, comprising a hydraulic machine operative at two different normal speeds dependent upon the variable net head, and an 15 alternating current dynamo-electric unit operable as motor or generator with different numbers of field poles and operatively connectible to said hydraulic machine, said dynamo-electric unit being operable to produce 20 electrical energy of the same frequency when driven at different ones of said two normal operating speeds.
7. The method of operating a hydro-electric machine having a plurality of alternators 25 associated therewith, which comprises, utilizing one of said alternators to maintain predetermined frequency for a definite range of speed of said machine, and utilizing another of said alternators to maintain the 30 same frequency for a different definite range of speed of said machine.
8. The method of operating a hydro-electric machine provided with a speed governor having a long range of regulating motion 35 and having a plurality of alternators associated therewith, which comprises, utilizing one of said alternators while limiting the extent of active regulating motion of said governor to an increment of its range to 40 produce constant frequency for said increment variation in speed, and utilizing another of said alternators while limiting the extent of active regulating motion of said governor to another increment of its range to 45 produce the same frequency for said other increment variation in speed.
9. A hydro-electric unit for generation 50 of alternating current of substantially constant frequency under conditions of widely varying head on the turbine element of the unit, comprising a hydraulic turbine element operative at a finite plurality of speeds dependent upon the head thereon, an electrical supply unit comprising a dynamo-electric 55 machine whose rotor is operatively associated with said turbine element so as to be driven thereby, through a driving connection of fixed speed ratio, and means whereby said electrical supply unit is caused to produce 60 electrical energy of a desired constant frequency independently of the particular one of said speeds at which said turbine element operates, said means including devices selectively operative to maintain a particular one of said speeds of operation 65 of said turbine element.
10. A power installation for generation of alternating current of substantially constant frequency under conditions of widely varying available supply of motive energy, comprising a prime mover, means for regulating said prime mover to maintain a plural finite number of operating speeds thereof, and an electrical generating element operatively connected to said prime mover to be 70 driven thereby through a driving connection of fixed speed ratio, said generating element being operable to produce electrical energy of a desired constant frequency independently of the particular one of said speeds at 75 which said prime mover operates to drive said generating element.
11. A power installation for generation of alternating current of substantially constant frequency under conditions of varying supply of energy available and consequent varying speed, comprising a prime mover operative at different normal speeds dependent upon the energy available at said prime mover, and an alternating current 80 generating unit including means for insuring 85 operation of said unit with different numbers of effective field poles, said generating unit being operable to produce electrical energy of said desired frequency when 90 driven by said prime mover operating at said different speeds and utilizing appropriate ones of said numbers of poles.
12. A power installation for generation of alternating current of substantially constant frequency under conditions of widely varying supply of energy, comprising an alternating current generator unit comprising a synchronous dynamo-electric machine, a prime mover mechanically connected to 100 said dynamo-electric machine and operable to drive said dynamo-electric machine at a finite plurality of different speeds dependent upon the supply of energy available, a distribution circuit, and means operative to 105 insure the supply of electrical energy from said generator unit to said distribution circuit at a predetermined frequency independently of the particular one of said speeds at 110 which said prime mover drives said dynamo-electric machine.
13. A power installation for production of alternating current of constant frequency under conditions of variable available supply of motive energy to said installation, 115 comprising a prime mover operable from a source of variable available supply of energy and operable at a finite plurality of speeds, an alternating current generating unit including a dynamo-electric machine connected to 120 said prime mover through a driving connection of fixed speed ratio, and means for regulating said prime mover to cause it to 125

maintain itself in operation at any one of said speeds, said generating unit being capable of producing alternating current of said constant frequency when said prime mover is operating at different ones of said speeds.

14. A power installation for production of alternating current of constant frequency under conditions of variable available supply of motive energy to the prime mover of said installation, comprising a prime mover operable from a variable supply of motive energy at a finite plurality of speeds dependent upon the supply of energy available, an alternating current supply unit comprising an alternating current dynamo-electric machine operatively connected to said prime mover to be driven thereby at different predetermined speeds dependent upon the speed of operation of said prime mover, and means for causing the speed of said prime mover to be maintained constant at any one of said speed values, said supply unit being operable to supply alternating current of constant frequency independently of the particular one of said speeds at which said dynamo-electric machine is driven by said prime mover.

15. The method of operating an electrical power installation including a prime mover operable under conditions of widely varying supply of energy therefor, and an alternating current dynamo-electric generating unit arranged for operation by said prime mover with different numbers of field poles, which comprises utilizing said alternating current generating unit under operation with one number of field poles to maintain a predetermined frequency over a definite range of variation in the supply of energy for said prime mover, and utilizing said alternating current generating unit under operation with another number of field poles to maintain the same frequency over another definite range of variation in the supply of energy for said prime mover.

16. A hydro-electric installation for the generation of alternating current of constant frequency under conditions of variable available head and varying speed of turbine incident thereto, comprising an alternating current dynamo-electric generating unit, a source of water supply of variable available head and a hydraulic turbine operable from said source to furnish energy for driving the rotary magnetic element of said dynamo-electric unit at a controlled speed dependent upon the available head of said source, and means for insuring the supply of electrical energy by said dynamo-electric unit at a predetermined fixed frequency independently of the particular one of said speeds at which the rotary magnetic element of said dynamo-electric unit operates, said latter

means including devices selectively operative to maintain any particular one of said operating speeds.

17. A hydro-electric installation for operation under conditions of substantially constant frequency and widely varying head, comprising a hydraulic machine operable at different predetermined normal speeds dependent upon the head on said machine, a synchronous alternating current dynamo-electric unit the rotatable magnetic element of which is operatively connected to said hydraulic machine for operation therewith, a distribution circuit the frequency of whose current is definitely established by means other than said unit, and means for insuring the operation of the rotatable magnetic element of said dynamo-electric unit at a plurality of synchronous speeds while said dynamo-electric unit is connected in power relation with said distribution circuit.

18. A power installation for the production of alternating current of constant frequency under conditions of widely varying supply of energy and varying speed of prime mover consequent thereto, comprising a synchronous alternating current generator unit, a prime mover mechanically connected to the rotatable magnetic element of said unit and operable to drive said magnetic element at different speeds dependent upon the supply of energy available, a distribution circuit carrying current of a frequency definitely established by means other than said generator unit, and means operative to insure the supply of electrical energy from said generator unit to said distribution circuit at the frequency of the latter independently of the particular one of said speeds at which the rotatable magnetic element of said generator unit is driven by said prime mover.

19. The method of regulating a hydro-electric installation comprising a hydraulic turbine, an alternating current generating unit, and a speed governor having a long range of regulating motion, which comprises limiting the extent of active regulating motion of said governor to an increment of its range to produce a predetermined controlled speed of operation of said turbine, and limiting the extent of active regulating motion of said governor to another increment of its range to produce a second controlled speed of operation of said turbine, and changing from one to another of said particular ranges of regulating motion in accordance with variations in a predetermined condition attendant upon the operation of said turbine.

20. The method of controlling a hydro-electric unit comprising a hydraulic turbine subject to widely varying head to cause said turbine to operate at any one of a plurality of

- substantially constant speeds independently of variations in load on said turbine, which comprises utilizing a speed governor of wide effective speed range, and compensating for
- 5 the operating effect of said governor to cause the maintenance of any one of said constant speeds during a relatively small part of the total range of said governor, and changing from one to another of said speeds of operation of said turbine in accordance with variations in the available head on said turbine.
